CLAIM

The ornamental design for a shoe as shown and described.

DESCRIPTION

FIG. 1 is a side view of a shoe showing my new design;

FIG. 2 is a rear perspective view thereof;

FIG. 3 is a rear view thereof;

FIG. 4 is an opposite side rear perspective view thereof; and,

FIG. 5 is an opposite side view thereof.

The broken line showing of the two racetrack shaped elements within the shaded area represent eyestay elements and form no part of the claimed design. The broken lines depicting the remainder of the shoe form no part of the claimed design.
